UNITED STATES PATENT OFFICE.

ALLEN F. RUFFIN AND ARTHUR L. WECKLER, OF WATERBURY, CONNECTICUT, ASSIGNEES TO SCOVILL MANUFACTURING COMPANY, OF WATERBURY, CONNECTICUT, A CORPORATION OF CONNECTICUT.

DESIGN FOR AN ATOMIZER SUPPORT OR SIMILAR ARTICLE.

Application filed May 23, 1928. Serial No. 26,824. Term of patent 14 years.

To all whom it may concern:

Be it known that we, ALLEN F. RUFFIN and ARTHUR L. WECKLER, citizens of the United States, residing at Waterbury, in the county of New Haven and State of Connecticut, have invented a new, original, and ornamental Design for an Atomizer Support or Similar Article, of which the following is a specification, reference being had to the accompanying drawing, forming a part hereof.

The figure is a side view of the atomizer support or similar article showing our new design.

We claim:

The ornamental design for an atomizer support or similar article as shown.

ALLEN F. RUFFIN.
ARTHUR L. WECKLER.
